UNITED STATES PATENT OFFICE.

JOSEPH LORENZ, OF ROBINSON, ILLINOIS.

UNDERREAMER.

1,136,543.

Specification of Letters Patent. Patented Apr. 20, 1915.

Application filed May 4, 1914. Serial No. 836,257.

To all whom it may concern:

Be it known that I, JOSEPH LORENZ, a citizen of the United States, residing at Robinson, in the county of Crawford and State of Illinois, have invented a new and useful Underreamer, of which the following is a specification.

This invention has reference to improvements in underreamers, and its object is to provide an underreamer which may be introduced through a small casing to drill the bore larger below the casing, so as to let the casing down as rapidly as the reamer enlarges the hole, and without interference with either the casing or the underreamer.

The underreamer of the present invention comprises an elongated body member carrying at the active end pivoted bits and wedge-like members for throwing the bits readily outward to the requisite distance to ream out a hole to a larger diameter than the casing for permitting the lowering of the latter. The spreading movement imparted to the bits is due to the action of a spring contained within the body member and controlling an elongated slide also within the body member and carrying the actuating wedges for the bits, while dogs are provided at opposite sides of the body member in position to hold the bit-actuating wedges projected to thereby release the bits to approach while the underreamer is being moved through the casing. The dogs have a normal tendency to move to a released position permitting the spring to act, and are so arranged as to move longitudinally of the body member for a limited distance, but may be locked at either extreme of their travel lengthwise of the body member.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is an elevation

of the underreamer within the casing, and the latter shown in diametric cross-section. 55 Fig. 2 is a longitudinal diametric section of the underreamer at right angles to the showing of Fig. 1, with some parts shown in elevation and the underreamer shown projected from the end of the casing. Fig. 3 60 is a section similar to that of Fig. 2 with the underreamer inside of the casing. Fig. 4 is an elevation of the underreamer within the casing and with the latter in section, the view being taken at right angles to that of 65 Fig. 1. Fig. 5 is a section on the line 5—5 of Fig. 2. Fig. 6 is a section on the line 6—6 of Fig. 1. Fig. 7 is a section on the line 7—7 of Fig. 1. Fig. 8 is a section on the line 8—8 of Fig. 1. Fig. 9 is a section on the line 9—9 of 70 Fig. 1. Fig. 10 is a perspective view of certain parts mounted in the body member, some in fixed relation thereto and others slideable lengthwise thereof. Fig. 11 is a perspective view of a latch dog forming part 75 of the structure. Fig. 12 is a perspective view of a trigger coacting with the latch dog of Fig. 11. Fig. 13 is a perspective view of one of the reaming bits. Fig. 14 is a perspective view of a key for holding the 80 reaming bits in place.

Referring to the drawings, there is shown a casing 1 such as is customarily used in deep wells, or deep borings, and it is also customary to employ in conjunction with such 85 casings a structure called an underreamer capable of enlarging the bore beneath the casing, so that the latter may be driven deeper into the ground.

The underreamer has a body portion 2 90 provided with a longitudinal axial bore 3 continued throughout the greater portion of the length from one end where the bore is threaded, as indicated at 4, for the reception of a screw plug 5 formed on the corresponding end of a drill rod 6 all in the customary manner. The body member 2 and drill rod 6 are provided with exterior flats 7 and 8, respectively, for the application of tools, whereby the body member 2 is 95 screwed tight on to the drill rod 6, as is customary.

The bore 3 stops short of the end of the body member 2 remote from the drill rod at a web 9, through which there is a central 100 passage 10, this passage being preferably

though not necessarily, rectangular, and somewhat wider in one direction than the other. Between the web 9 and the end of the body 2 remote from the drill rod, said body is formed with longitudinal recesses 11 on opposite sides of a diametric web 12, the latter being formed with a longitudinal slot 13 extending from the passage 10 toward its outer end for an appropriate distance. On opposite sides of each slot the walls thereof are formed with inturned shoulders 14, each having one end 15 next to the closed end of the recess substantially perpendicular to the bottom of the recess, while the other end 16 is inclined outwardly, so that the shoulder is substantially there undercut.

Since the underreamer in operation is usually upright with the drill rod 6 fast to its upper end, expressions of position found hereinafter have reference to the normal operative position of the underreamer, so that the end of the body member to which the drill rod is attached may be termed the upper end, while that provided with the recesses 11 and central web 12 may be termed the lower end. The upper end of each recess 11 terminates in a shoulder 17 carrying spaced pins 18, while lodged in each recess is a reamer bit 19 having recesses 20 on opposite sides conforming generally in shape to the shoulders 14, but with the recesses of somewhat greater length than the shoulders, one end 21 of each recess being slightly inclined toward the corresponding or upper end of the reamer bit, while the other end of the recess is formed into an inclined shoulder 22 of nearly the same inclination as the shoulder 16.

That end of the reaming bit which may be termed the upper end and close to the shoulders 21 is formed with spaced sockets 23 for the reception of the pins 18, while the other or lower end 24 of the bit is appropriately shaped for cutting, the outer face of the bit being convex on an arc substantially that of the casing to produce a cut conforming generally to the contour of the casing.

The web 12 in line with the shoulders 15 is provided with passages for keys 25, one of which is shown separately in Fig. 14. These keys reach to the surface of the body of the reamer, and are appropriately curved or beveled in conformity with the cylindrical shape of the body, and on one long face about midway of its length each key is provided with a notch 26 for a locking pin 27 which may be in the form of a screw or be otherwise shaped, and these pins 27 are introduced into the body of the reamer from opposite sides thereof, so as to enter the notches 26, and thus hold the keys from escape after being once placed in position. The keys 25 are of such width as to approximately fill the space between the shoulders

15 and 21, and the shoulders 21 may be slightly rounded to permit a limited rocking movement of the reamer bit without interference from the keys 25, while the pins 18 and sockets 23 are suitably related to permit such limited rocking movement. 70

The body 2 within that portion provided with the bore 3 is formed with longitudinal slots 28 on diametrically opposite sides, both slots opening on their inner sides into the bore 3, and each slot having in its opposite walls a longitudinally spaced series of matching notches 29, the slots and, notches being for a purpose to be described. 75

Mounted in the bore 3 is a block 30, and since the bore 3 is customarily cylindrical, the block 30 is likewise cylindrical. At one end the block is provided with an axial stem 31, the stem being of rectangular cross section conforming to the passage 10 and for a portion of its length the stem is recessed at the sides, as shown at 32, to receive tongues 33 on the corresponding ends of other stems 34 carrying at the ends remote from the stems wedge blocks or heads 35, each terminating at the free end in a beveled portion 36, the bevels of the beveled ends of the heads 35 being one toward the other. Each head where joining the stem 34 approaches the stem at an angle forming a bevel 37. 90

The stems 34 are for a portion of their length narrower than the heads 35, thus forming shoulders 38. The narrow portions of the stems 34 are of a width to slide freely between the shoulders 14, and the heads 35 are of a width to slide freely in the wider lower portions of the recesses 11, while the tongues 33 are of the same width as the stem 31 where they are secured to it, the securing means in the present instance being shown as screws 39. The extreme lower end of the stem 31 is provided with oppositely directed lugs 40 entering slots 41 through the stems 34 near where the tongues 33 project therefrom. The lugs 40 coact with the screws 39 to hold the wedge-like heads 35 to the stem 31 and the slots 41 may be slightly wider than the lugs 40 to permit a very limited side play, so that the parts readily conform to any irregularities which may exist between the bore 3 and the recesses 11 constituting channels along which the heads 35 may travel, and in which the reamer bits are lodged, so as to rock in part into and out of these recesses or channels. 110

It will also be understood that the lugs 40 may fit snugly in the recesses 41. The purpose of making the heads 35 separate from the stem 31 is to permit assembling of the parts. 120

Projecting from that end of the block 30 remote from the stem 31 are two elongated guide fingers 42 emerging from diametrically opposite sides of the corresponding end of the block 30 and from an intermediate 125

point each finger is of lessened thickness, as indicated at 43. Each finger is pierced near the free end by a perforation 44.

Adapted to the fingers is a cap disk 45 suitably recessed on opposite sides, as shown at 46, and when the cap disk 45 is applied to the fingers it is held thereto by a staple 47.

Applied to the fingers 42 is another block 48 having diametrically opposite longitudinal grooves 49 in which the fingers are seated, and along which they may be moved, while on diametrically opposite sides of the block 48 on a diameter substantially at right angles to the grooves 49 are hollow longitudinal recesses 50 terminating in inclined shoulders 51 approaching the center line of the block from opposite sides thereof, and from these shoulders the block is formed with widened surfaces 52 in turn terminating in other inclined shoulders 53 directed toward the center line of the block and ending in a wedge shaped tongue 54. The flattened surfaces 52 are closer to a longitudinal diametric plane intermediate of and coinciding with the grooves 49 than are the bottoms of the recesses 50, while the tongue 54 has its sides merging at such diametric plane.

The block 48 close to the end remote from the tongue 54 is pierced by a passage 55 perpendicular to the diametric plane coinciding with the grooves 49 and extending through this passage is a pin 56 lodged in an appropriate portion of the body 2 and closer to the end carrying the drill rod 6 than are the slots 28. The pin 56 holds the block 48 firmly against movement in the body 2 and said block constitutes an abutment for a helical spring 57 surrounding the extension 43 of the fingers 42 between the disk 45 and the block 48, the tendency of the spring being, therefore, to hold the disk 45 as far away from the block 48 as is permitted by the engagement of other parts.

Adapted to the surfaces 50 and 52 of the block 48 are elongated triggers 58, one of which is shown separately in Fig. 12. The trigger has at one end a right-angular extension 59 with its outer end beveled as shown at 60. For about half the length of the trigger at the end remote from the extension 59 the thickness of the trigger is reduced as shown at 61, and the thin portion and thicker portion are joined by a beveled shoulder 62, while the extreme end 55 of the reduced portion 61 is beveled as shown at 63. That long side of the trigger from which the extension 59 projects is oppositely inclined, or prismatic, as indicated at 64. There are two triggers 58 with the stepped surface remote from the triangular or beveled surface 64 adapted to the surfaces 50 and 52, while the shoulders 62 and 63 are adapted to the inclined portions 51 and 54 of the block 48. When so applied the right-angular extensions 59 project op-

ositely one from the other into and through the slots 28, the extensions 59 having their beveled ends 60 terminating at about the surface of the body member 2.

Lodged in each slot 28 is a latch dog 65, 70 one of which is shown separately in Fig. 11. Each dog is in the form of an elongated block of a thickness to fit snugly, yet freely in a respective slot 28, and is sufficiently shorter than the slot to move longitudinally 75 of the body member 2 for a limited distance. One edge of the latch dog is provided with a triangular or beveled longitudinal groove 66 bordered by divergent tongues 66^a and adapted to the beveled or prismatic edge 64 80 of the trigger, and one end of this grooved edge is beveled, as indicated at 67, in conformity with the bevel of the shoulder 63. The corresponding end of the other edge of the latch dog is formed with a bevel 68, 85 while at appropriately spaced points the latch dog is traversed by pins 69 adapted to the recesses 29 of the respective slots 28, this spacing of the pins being the same as the spacing of the notches 29, but while each 90 dog is provided with two spaced pins each slot 28 has three correspondingly spaced notches 29.

The block 48 acts as a wedge-like spreader for the triggers 58 along which latter the 95 latch dogs 65 are movable lengthwise of the reamer body.

When the parts are all assembled, and the reamer is introduced into the casing 1, the various structures are related as shown 100 in Fig. 3. The triggers have their angle extensions 59 in engagement with those ends of the slots 28 remote from the drill rod 6. At the same time the latch dogs 65 are lodged at what may be termed the upper ends of the slots 28; that is, the ends toward the rod 6. Under these circumstances the block 30 has been moved along the bore 3 until close to the web 9 with the end from which the fingers 42 project in 110 abutment with the projections 59 of the triggers 58. In this position of the parts the block 48 is sufficiently distant from the block 30 to permit the thicker portions of the triggers to lodge between the beveled tongue 54 and the block 30 with the inner portions of the triggers resting upon the surfaces 52 and the shoulders 62 in engagement with the shoulders 53 and tongue 54. The spring 57 is under these circumstances compressed 115 as shown in Fig. 3, while the latch dogs 65 are approached one toward the other until their outer edges are about coincident with the surface of the reamer body and the pins 69 are seated in the corresponding recesses 29. The tendency of the compressed spring 57 is to move the block 30 and parts carried thereby toward the end of the body 2 remote from the reamer bits, but this is resisted by the latch dogs which at the time 120 125 130

have their pins 69 seated in the notches 29, and consequently these dogs hold the triggers 58 from movement either longitudinally of the body member or laterally away 5 one from the other, and the triggers in turn hold the block 30 against movement under the action of the spring 57. With the parts in the position described the beveled heads 35 are projected beyond the cutting end of 10 the reamer and consequently are out of the path of the reaming bits 19, so that the latter are readily swung on their hinge pins 18 one toward the other until the spread of these bits is so greatly reduced that they 15 may be introduced within the casing 1. When within the casing the latch dogs 65 have no room to move one away from the other to carry the pins 69 out of the notches 29, and consequently the locked condition of 20 the reamer continues.

The reamer is lowered until the latch dogs move beyond the lower edge of the casing 1, whereupon the latch dogs are readily moved outwardly because they do not resist any more a spreading movement of the triggers and the latter therefore yield to the action of the spring 57 to move both longitudinally and laterally forcing the pins 69 of the dogs 65 out of the recesses 29. 25 The longitudinal movement of the block 30 and parts carried thereby causes the heads 35 to enter between the reaming bits and expand them into operative position.

When the underreamer is to be withdrawn it is lifted until the bottom edge of the casing engages the beveled shoulders 68 of the latch dogs, thus holding these latch dogs while the reamer continues the upward movement and the latch dogs ultimately reach the lower ends of the slots 28, whereupon being constrained to move with the rising reamer the reaction of the lower edge of the casing against the beveled ends 68 causes the latch dogs to approach one 40 toward the other, and ultimately seat in the corresponding recesses 29. In the meantime the continued upward movement of the reamer has not been participated in by the triggers 58, nor by the block 30, so the 45 spring 57 is compressed by the block 48 fast to the body of the reamer and the bits 19 are moved away from the beveled heads 35, so that they may readily approach one toward the other to enter the casing 1.

50 55 What is claimed is:—

1. In an underreamer, an elongated body member, reamer bits carried thereby, bit expanding means in and movable longitudinally of the body member in opposite directions, a spring constraining the bit expanding means to move in the active direction, triggers movable with the bit expanding means and also laterally thereto, the trigger and bit expanding means having 60 65 coacting portions for causing the lateral

movement of the triggers, and longitudinally movable dogs carried by the body member, said dogs, triggers and body member having coacting portions for locking the dogs and triggers at either limit of longitudinal movement of the dogs. 70

2. In an underreamer, an elongated body member, reamer bits carried thereby, bit expanding means in and movable longitudinally of the body member in opposite directions, a spring constraining the bit expanding means to move in the active direction, and longitudinally movable dogs carried by the body member, said dogs coacting with the bit expanding means and the dogs and 75 body member having coacting locking means for positively holding the dogs at either limit of their travel to in turn lock the bit expanding means in the inactive position in opposition to the normal tendency of the 80 spring. 85

3. In an underreamer, an elongated body member, reamer bits carried thereby, bit expanding means in and movable longitudinally of the body member in opposite directions, and longitudinally movable dogs carried by the body member for locking the bit expanding means in the inactive position at 90 either limit of longitudinal travel of the dogs, said dogs and body member having coacting means for positively locking the dogs at the opposite limits of their travel in the body member. 95

4. In an underreamer, an elongated body member, reamer bits carried thereby, bit expanding means in and movable longitudinally of the body member in opposite directions, and longitudinally movable dogs carried by the body member for locking the bit expanding means in the inactive position at 100 either limit of longitudinal travel of the dogs, said dogs and body member having coacting means for positively locking the dogs at the opposite limits of their travel in the body member, and said dogs being movable 105 bodily in directions laterally to their longitudinal travel and having portions exposed at the surface of the body member. 110

5. In an underreamer, an elongated body member with intermediate longitudinal slots 115 on opposite sides, reamer bits mounted on the body member, bit expanding means within the body member and movable longitudinally thereof, and locking dogs mounted in the body member and projecting through 120 and movable longitudinally of the slots for locking the bit expanding means in the inactive position at either limit of travel of the dogs in the slots, said dogs being also movable laterally of the body member, and 125 said dogs and body member having coactive means for positively locking the dogs against longitudinal movement at either limit of their longitudinal movement in the slots. 130

6. In an underreamer, an elongated body member with intermediate longitudinal slots on opposite sides, reamer bits mounted on the body member, bit expanding means within the body member and movable longitudinally thereof, and locking dogs mounted in the body member and projecting through and movable longitudinally of the slots for locking the bit expanding means in the inactive position at either limit of travel of the dogs in the slots, said dogs being also movable laterally of the body member, and said dogs and body member having coactive means for positively locking the dogs against longitudinal movement at either limit of their longitudinal movement in the slots, said locking means consisting of projecting pins on the dogs and spaced recesses in the walls of the slots.
7. In an underreamer, an elongated body member with intermediate longitudinal slots on opposite sides, reamer bits mounted on the body member, bit expanding means within the body member and movable longitudinally thereof, and locking dogs mounted in the body member and projecting through and movable longitudinally of the slots for locking the bit expanding means in the inactive position at either limit of travel of the dogs in the slots, said dogs being also movable laterally of the body member, and said dogs and body member having coactive means for positively locking the dogs against longitudinal movement at either limit of their longitudinal movement in the slots, said locking means comprising a pair of pins on each dog spaced longitudinally thereof, and pairs of spaced recesses in the side walls of the slots spaced apart corresponding to the pins, the number of pairs of recesses in each slot exceeding the number of pins in a dog by one.
8. In an underreamer, an elongated body member, reamer bits carried thereby, bit expanding means in and movable longitudinal of the body member in opposite directions, a spring constraining the bit expanding means to move in the active direction, triggers carried by the body member and movable with the bit expanding means and also laterally thereof, operating means for the triggers carried by the body member, and said triggers and operating means having coactive beveled portions for causing lateral movement of the triggers, and longitudinally movable dogs carried by the body member in coactive relation to the triggers, said dogs and body member having coactive means for locking the dogs at either limit of their travel in coactive relation to the triggers.
9. In an underreamer, an elongated body member, reamer bits carried thereby, longitudinally movable bit expanding means in the body member, a spring constraining the
- bit expanding means to move in the active direction, triggers mounted in and movable longitudinally of the body member in operative relation to the bit expanding means, each trigger having beveled shoulders, corresponding beveled shoulders in fixed relation to the body member and in operative relation to the beveled shoulders of the triggers, and longitudinally movable dogs mounted in and extending to the surface of the body member, said dogs being movable along the triggers lengthwise thereof, and the dogs and body member having coactive means for holding the dogs in engagement with the triggers, and to hold the dogs against longitudinal movement at each limit of their travel.
10. In an underreamer, an elongated body member, reamer bits carried thereby, longitudinally movable bit expanding means in the body member, a spring constraining the bit expanding means to move in the active direction, triggers mounted in and movable longitudinally of the body member in operative relation to the bit expanding means, each trigger having beveled shoulders, corresponding beveled shoulders in fixed relation to the body member and in operative relation to the beveled shoulders of the triggers, and longitudinally movable dogs mounted in and extending to the surface of the body member, said dogs being movable along the triggers lengthwise thereof, and the dogs and body member having coactive means for holding the dogs in engagement with the triggers, and to hold the dogs against longitudinal movement at each limit of their travel.
11. In an underreamer, a body member with a longitudinal bore shorter than the body member and with opposite recesses communicating with the bore, reamer bits mounted in the recesses and movable laterally with respect thereto, a bit expanding means mounted in the bore and movable longitudinally thereof and having an extension entering the recesses, bit expanding wedges separate from and attached to the bit expanding means, and devices for locking the bit expanding means in the inactive position.
12. In an underreamer, an elongated body member, bits mounted thereon, and bit expanding means in the body member comprising a reciprocating block with diametrically separated fingers projecting longitudinally from one end of the block, and a stem projecting from the other end of the

block, a guide block fixed in the body member and provided with longitudinal grooves on diametrically opposite sides for receiving the fingers in straddling relation to the 5 block, a stop member fast to the free ends of the fingers, a spring surrounding the fingers between the guide block and the stop member, wedge heads separate from and fast to the stem of the first-named block in 10 position to enter between the bits to expand them, and means for locking the bit expanding means in the inactive position.

13. In an underreamer, an elongated body member, bits mounted thereon, and bit expanding means in the body member comprising a reciprocatory block with diametrically separated fingers projecting longitudinally from one end of the block, and a stem projecting from the other end of 20 the block, a guide block fixed in the body member and provided with longitudinal grooves on diametrically opposite sides for receiving the fingers in straddling relation to the block, a stop member fast to the free 25 ends of the fingers, a spring surrounding the fingers between the guide block and the stop member, wedge heads separate from and fast to the stem of the first-named block in position to enter between the bits to 30 expand them, and means for locking the bit expanding means in the inactive position.

said locking means comprising longitudinally movable triggers with the triggers and guide block formed with wedge-shaped portions to cause lateral movements of the 35 fingers, and dogs movable longitudinally in the body member and having portions exposed to the surface thereof, said dogs and triggers having coactive portions for engagement and the dogs and body member 40 having coactive locking means for holding the dogs at either limit of their longitudinal movement, and the dogs being laterally movable in the body member and provided with means for limiting lateral movement 45 outwardly with respect to the body member.

14. In an underreamer, a body member having oppositely disposed recesses at one end, and reaming bits mounted in the recesses, the closed ends of the recesses and the corresponding ends of the reaming bits being provided with coactive pin and socket 50 connections for movement of the active ends of the reaming bits thereabout.

In testimony, that I claim the foregoing 55 as my own, I have hereto affixed my signature in the presence of two witnesses.

JOSEPH LORENZ.
